UNITED STATES PATENT OFFICE.

JAMES B. MOORE AND JOHN P. ROBITZER, OF PITTSBURG, PENNSYLVANIA.

DESIGN FOR SIGNS.

Specification forming part of Design No. 5,227, dated August 22, 1871.

To all whom it may concern:

Be it known that we, JAMES B. MOORE and JOHN P. ROBITZER, of Pittsburg, in the county of Allegheny and State of Pennsylvania, have invented a new and useful Design for Signs; and we do hereby declare the following to be a full, clear, and exact description thereof.

Our improved design is illustrated by the accompanying photographs, which are hereby made a part of this specification; and consists in the figure of an eagle suspended from a suitable bar or frame, and carrying a ribbon or band which is wrapped in successive, but separated, and open folds around an initial letter, H, as illustrated in the photographs. The folds of the ribbon or band are made to conform somewhat to the shape of the letter employed, but are substan-

tially that shown. The ribbon or band constitutes the sign-board of the person or firm using it. It is also made Janus-faced, and is designed to be hung at right angles, or nearly so, to the direction of the street.

What we claim as our improved design is—

The suspending-bar or frame, eagle, and folding or winding sign-ribbon, of the form and arrangement described and shown.

In testimony whereof we, the said JAMES B. MOORE and JOHN P. ROBITZER, have hereunto set our hands.

JAMES B. MOORE.
JOHN P. ROBITZER.
